UNITED STATES PATENT OFFICE.

DWIGHT A. NILES, OF WINDSOR, VERMONT.

EDGE-TRIMMER.

1,115,963.

Specification of Letters Patent.

Patented Nov. 3, 1914.

Application filed August 2, 1913. Serial No. 782,635.

To all whom it may concern:

Be it known that I, DWIGHT A. NILES, a citizen of the United States, and a resident of Windsor, in the county of Windsor and State of Vermont, have invented certain new and useful Improvements in Edge-Trimmers, of which the following is a specification.

This invention relates to improvements 10 in machines for trimming the edges of shoe soles and particularly to that class adapted to operate before the heels have been applied to the shoes and while the latter contain the lasts or other internal supporting forms.

The objects are first, to provide a mechanism that will trim the soles of shoes uniformly with respect to the contour of the last or form, irrespective of their thickness 20 and with any desired degree of bevel.

A second object is to provide means whereby the shoe is guided and controlled by automatically operated means that assure rapidity, uniformity and precision of 25 results, in addition to the usual hand guiding means.

Third, to provide devices combined with the mechanism that prevent any possible injury to the upper from the cutter, and 30 which are applicable to any size, kind or shape of shoe whatever without the use of extra parts or loss of time in changing.

These and other objects are attained by the novel combination and construction of 35 parts hereinafter fully described and shown in the accompanying drawings, in which:

Figure 1 is a plan view of an edge trimmer made in accordance with the invention. Fig. 2 is a front elevation of the same. 40 Fig. 3 is a view looking from the left hand end of the same. Fig. 4 is a partial cross section, taken on line 4-4 of Fig. 1. Fig. 5 is an enlarged fragmentary plan view of the guide or shoe gaging elements. Fig. 6 45 is a plan view of a fragment of the table. Fig. 7 is an enlarged view showing a section of the gage and tables illustrating the relation of the shoe and cutter.

The invention comprises a table 10 having end supports 11 integrally connected at 12 and 13 at the front, both of which connections carry alined bearings 14 and 15 being lower and upper respectively; in these bearings is revolvably mounted a vertical shaft 16 formed with a step at its lower end 17 and having a cutter 20 affixed at its

extreme upper end; secured on the shaft 16 is a flanged pulley 21 driven by a quarter turn belt 22 from the pulley 23 secured on the horizontal shaft 25, the same being mounted in bearings longitudinally of the machine at its rear and constituting the main drive shaft having the drive pulleys 24 at its end; also on this shaft is another pulley 26 having a quarter-turn belt 27 leading to the driven pulley 28 on the vertical shaft 30 mounted in bracketed bearings 31 and 32 extending from the left hand support 11; at the upper end of the shaft 30 above the bearing 32 is a smaller flanged 60 driving pulley 33 having another quarter-turn belt 34 leading to the pulley 35 loosely mounted on a short shaft 36 carried in bearings 37 and 38 transversely of the machine, below the lower surface of the table 10 and 65 central of the machine, substantially in alinement with the cutter shaft 16, but at a right angle thereto.

On the shaft 36 is keyed a friction clutch 38 so as to slide thereon and engage with the pulley 35 by means of the clutch lever 39, fulcrumed at 40 and actuated through the pull rods 41 and 42 by the treadle lever 44 pivoted to the frame at 45; interposed between the pull rods is the end of a lever 43 pivoted at 46 to a link 47 engaged with an extension of the bracket arm 48, the lever being spaced and having arms 49 embracing and pivotally connecting with a sleeve 50 arranged on the hollow vertical 75 bar 52 having a stop 53 at its lower end and being slidable within the bracket 55.

The bar 52 contains a central opening to which is loosely fitted a stem 56, the same being screw-threaded and provided with a hand-wheel 58 having a hub adapted to rest upon the sleeve 50 in such manner that it can be raised or lowered relative thereto, and independent of any rectilinear movement that may be imparted through the depression of the treadle 44.

The stem 56 supports a bracket 60 having side arms 61 to which are hingedly secured a pair of lugs 62 extending down near the ends at the base of the semi-circular table 65, a similar lug 63 being centrally disposed at the front, the same having connected thereto a rod 66 passing down through the front of the bracket 60 in such manner as to be adjustably secured therein 105 by the wing-screw 67. Thus it is readily possible to either raise or lower the table 110

65 by means of the hand-wheel 58, the action constituting a substantially permanent adjustment, or by operating the treadle a temporary adjustment is obtained; by 5 means of the hinged connections to the table and the adjustable rod 66 the table may be tilted to such an inclination as may be desired.

A carriage 70 is arranged to move length- 10 wise of the main table 10 in grooves 71 formed therein and has upon its surface at each end, slotted arms 72 adjustable laterally of the carriage and secured by screws 73 at desirable points. Midway of the carriage is also adjustably fastened a bracket 74 bored to receive the stem 78 of a holder 80, the same having a shoulder at the front and having a collar 79 on the opposite side of the bracket; the extended front of the 15 holder 80 is recessed to receive a plurality of independently adjustable guide supports 82 having at their front ends means adapted to pivotally support short guide sections 84, extending between adjacent pairs of the 20 mentioned supports to which they are pivotally secured; arms 85 extend outward from the body portion of the holder 80 and are suited to receive pivots connecting with the main portions 86 of the guide, the same 25 being extended to reach and be pivotally secured to the first mentioned adjustable arms 72. Thus it will be seen that the guide members present a substantially continuous face extending the full length of 30 the carriage and that the guide is adjustable to suit varying conditions, both as to outline presented and position required. Below the carriage is a rack 90 adapted to engage with a spur gear 91 mounted on the 35 shaft 36, which by reason of the friction clutch 38 can be operated at will through the treadle 44 so that rectilinear motion may be transmitted to the carriage 70. Upon release of the treadle the carriage is 40 returned to its original position by means of the counter-weight 95 attached to a chain or cord 96 running through an opening in the table and between the guide pulleys 97 and having its end secured to the carriage. 45 When the carriage 70 is at rest under the influence of the weight 95 the cutter 20 is at the right hand end of the guide.

On the top of the table 10 immediately back of the cutter 20 is fastened a bracket 50 100 having an arm partially overhanging the cutter and carrying a loosely mounted wheel 102 with which the guide is adapted to engage so as to be held against vertical movement with relation to the cutter.

60 The front face of the guide is constructed to engage with the shoe upper immediately above the sole and is shaped to conform to such portion of the upper. The guide is provided with an index 103 to indicate the initial positions in which dif-

ferent sizes of shoes shall be placed on the table 65, at that time depressed or lowered by reason of gravity, each size of shoe being placed on the table with the point on the sole edge at the widest and lowest portion of the sole coinciding with the index mark which brings the toe of the sole central with the guide in the trimming operation.

The trimming operation begins at the in- 75 side of a left shoe and at the outside of a right shoe, continuing toward and around the toe and thence along the opposite side to the curved portion corresponding with the starting point, this being the main part 80 of the trimming operation and that which requires the greatest skill. From the foregoing it will be seen that the width of the sole depends on the distance from the guide to the periphery of the cutter and that this 85 distance can be varied to suit at any point.

The depression of the treadle moves the work table with the shoe upon it upward into position to be operated upon by the cutter and coincidentally with the full rise of 90 the table, the clutch is engaged, starting the carriage and guides to move past the cutter; if now the shoe be moved by hand in unison with the guide, the cutter will trim the sole to the desired outline; if it is de- 95 sired to trim the shoe sole so as to extend beyond the upper on the edge opposite or away from its mate and closer on the inside or adjacent edge the ends of the guide are adjusted obliquely to the straight edge 100 of the table so as to present an obtuse angle against which the shoe may contact, while the center part of the guide may be curved to suit the shape of the toe; each part of the guide is movable separately in and out 105 so that the change on the toe will be gradual and not all in one place; a broad toed shoe is sometimes left full along the sides to the toe in which case the guides are adjusted to present substantially a straight 110 line to the shoe, which contains a last or follower so that its outline may be maintained.

The hand wheel 58 is for the purpose of 115 adjusting the full rise of the table whereby the machine is adapted for operating on various thicknesses of soles; a beveled edge is obtainable by means of the devices for inclining the table.

The machine is adapted particularly for 120 trimming soles from the ball or point of extreme side extension on one side to a corresponding point on the other, including the toe; this part of the sole is trimmed with one cutter while a different cutter is used 125 on the shank or that portion of the sole between the ball and heel. Thus it will be seen that the machine is capable of being operated without damage to the shoes, that it will take all kinds and sizes 130

without extra parts, that the adjustments are readily made and that a greatly increased product can be obtained.

Having thus described my invention, 5 what I claim as new and desire to secure by Letters Patent, is:

1. An edge trimmer comprising a revolvable cutter, a work table normally below the plane of said cutter, means for inclining said table, and means for elevating said table to its operative level including means for adjusting the relative working height of said table with respect to said cutter.
2. In an edge trimmer, the combination 15 with a revolvable cutter, a vertically movable operating table, means for raising said table and means for limiting the height to which said table can be raised, of an adjustable work guide and means for moving said guide lengthwise of said table.
3. An edge trimmer comprising a revolvable cutter, a main table, a carriage movable thereon, a work table normally below the plane of said cutter, an adjustable guide attached to said carriage, an index on said guide for indicating the initial position in which the work should be placed on said work table, adjustable means for elevating said table to its operative level, and means 25 for moving said carriage past said cutter arranged to initiate such movement simultaneously with the completion of the elevation of said table.
4. An edge trimmer comprising a revolvable cutter, an operating table upon which work may be manipulated, a guide for the work and means for advancing said guide past said cutter to guide the work to said cutter, said guide being arranged to adjustably control the position of the work with respect to the cutter.
5. An edge trimmer comprising a revolvable cutter, an operating table upon which the work may be manipulated, said table be-

ing normally below the plane of said cutter, 45 means for raising said table including means for adjusting the height to which said table can be raised, an adjustable guide for the work, and means for advancing said guide past said cutter, said guide advancing means 50 being timed to become operative upon the completion of the rise of said table.

6. In an edge trimmer, the combination with a revolvable cutter, and a work table, 55 of a work guide consisting of end elements and a plurality of shorter elements disposed therebetween, means for flexibly connecting the adjacent ends of all of said elements, means for adjusting said elements separately so as to produce a substantially unbroken face of variable contour and means for moving said guide past said cutter.

7. In an edge trimmer, the combination with a revolvable cutter and a work table, of a work guide comprising a plurality of 65 separately adjustable units so arranged as to present a substantially unbroken face, means for moving said guide from a position of rest in one direction past said cutter and in close proximity to said table, and means 70 independent of said last-named means for returning said guide to its original position.

8. In an edge trimmer, the combination with a revolvable cutter, and an adjustable work table, of a work guide comprising laterally adjustable and longitudinally movable units having a groove formed in their rear sides, and a fixed guide roller operating in the groove to maintain the guide units in the same horizontal plane during their longitudinal movement.

In testimony whereof I have signed my name to this specification in the presence of two subscribing witnesses.
